UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

IGNITION-DYNAMO.

1,351,502.

Specification of Letters Patent.

Patented Oct. 5, 1920.

Application filed November 18, 1918. Serial No. 263,027.

To all whom it may concern:

Be it known that I, CHARLES THOMAS MASON, a citizen of the United States, residing at Sumter, in the county of Sumter 5 and State of South Carolina, have invented certain new and useful Improvements in Ignition-DYNAMOS, of which the following is a specification, reference being had to the accompanying drawing.

10 The invention relates to new and useful improvements in an ignition apparatus for an internal combustion engine, and more particularly to a magneto ignition device for furnishing sparks to an internal combustion engine having the cylinders thereof inclined to each other.

It is well understood that the sparks for an engine of the above character must be furnished at unequal angular intervals in 20 the rotation of the engine shaft. In the patent granted to Honold November 8th, 1910, No. 974,967, there is shown and described a magneto ignition device for furnishing ignition sparks at unequal angular 25 intervals for a V-type engine—that is, an engine wherein the cylinders are inclined to each other. In this magneto current generating device, the flux flows from one section of a flux producing element angularly across to another section and as the armature rotates the angle is shifted, the flux flowing from one section to the other and thus the angular spacing of the sparks 30 is secured. This shifting of the flux creating section requires a large flux generating element, as part of the flux generating element is ineffective at certain times in the 35 rotating of the armature.

In the patent to Cunningham, granted 40 November 9th, 1916, there is shown a magneto electric generator especially adapted for a V-type engine, in which this objectional shifting of the flux is avoided and the relative size of the flux producing 45 elements greatly reduced by the shaping of the metal in the armature core so that the reversal of the flux through the core occurs at unequal angular intervals. In this Cunningham structure the shaping of the core 50 of the armature produces wide air gaps at certain flux reversals which decreases the efficiency of the structure. Furthermore, in

both the Cunningham and Honold structures the generating coil rotates and is, therefore, more or less inaccessible.

An object of the present invention is to provide an ignition device wherein the generating coil is separate and independent from the rotating parts, so that it may be readily removed for inspection.

A further object of the invention is to provide a magneto ignition device, wherein there is a fixed magnetic field and a portion of the flux due thereto is rotated about an axis parallel with the direction of the flux 65 and means is provided for intermittently completing the path of said rotating flux portion through a stationary current generating coil, but at unequal angular intervals in the rotation of the flux.

A still further object of the invention is to provide a magneto ignition device of the above character, wherein an interrupter is provided for interrupting the primary of the generating coil in angular timing with 75 the intermittent completing of the path of the flux through the coil.

A still further object of the invention is to provide a magneto electric device for an ignition system of the above character, 80 wherein the generating coil, the condenser and the distributor points are all mounted on a unitary structure so that said parts may be removed as a unit and replaced in the magneto at will.

A still further object of the invention is to provide a magneto electric generator having a fixed generating coil and a rotor for intermittently completing the path of flux through the generating coil, which 90 rotor is provided with a plurality of pairs of lobes, the lobes in each pair being disposed so that the centers thereof are less than one hundred and eighty degrees apart, whereby the flux flow through the generating coil is intermittently completed by said lobes at unequal angular intervals in the rotation of said rotor.

These and other objects will in part be obvious and will in part be hereinafter more 100 fully described.

In the drawings which show by way of illustration one embodiment of the invention—

Figure 1 is a longitudinal sectional view through a magneto electric generator having my improvements embodied therein;

Fig. 2 is a view showing more or less diagrammatically, the rotor, the generating coil and the distributor;

Fig. 3 is a diagrammatic view showing the relation of the rotor to the pole pieces and the generating coil, also to the interrupter and the distributor;

Fig. 4 is a view showing more or less diagrammatically the position of the pole pieces and the rotor and the interrupter at the time of ineffective flux change;

Fig. 5 is a similar view, but showing the parts positioned for producing the second spark in the rotation of the rotor;

Fig. 6 is a similar view, but showing the flux change at an ineffective spark interval, the interrupter being closed;

Fig. 7 is a view similar to Fig. 5, but showing a slightly modified form of the invention in the shaping and the arrangement of the lobes of the rotor, the parts being positioned for the first sparking interval;

Fig. 8 is a similar view, but showing the parts positioned for the second sparking interval.

The invention is directed broadly to a magneto electric generator for generating a current for ignition purposes, and particularly for furnishing ignition for a V-type engine—that is, an engine having the cylinders inclined to each other. Assuming there are two cylinders, it is well known that the sparks for the cylinders must occur at $360^\circ + X^\circ$ on one cylinder and $360^\circ - X^\circ$ on the other cylinder, where X is the angle in degrees between the cylinders. If the magneto generating shaft rotates at half the speed of the engine shaft, then in order to produce an efficient spark the current in the generating coil must rise to a maximum at the angular intervals of $180^\circ + \frac{X^\circ}{2}$ and $180^\circ - \frac{X^\circ}{2}$.

Magneto generators have been designed which will produce maximum current generation at these unequal angular intervals. The Honold patent, above referred to, shows one type of magneto electric generator, the angular intervals in this type of magneto being secured by the causing of the flux to flow diagonally from one flux generating portion across to another generating portion, this angular path of flux being caused to shift to another diagonal position and the shifting is brought about at unequal angular intervals. The objections to a magneto electric generator of this character are numerous, and possibly the one most noticeable is the excessive amount of material required in constructing the generator as only a portion of the flux generating element is

effective at one time. In the Cunningham type of generator, above referred to, the entire flux generating element is continuously effective and the amount of material necessary to construct the same is greatly reduced. The shifting of the flux in this type at unequal intervals is brought about through the shaping of the core or pole tips of the armature, and the unequal spacing of the sparks or maximum rise in the generating coil is accomplished at a considerable sacrifice of the current rise in connecting with one of the sparks. Furthermore, in both of these types of generators, as noted above, the generating coil is a rotating coil, which is more or less inaccessible.

My invention is directed to a magneto electric generator, wherein the coil is stationary and entirely independent of the rotating parts. The generator includes a means for creating a constant magneto motive force, constituting a fixed magnetic field. This is preferably brought about by the use of permanent magnets. A portion of the flux due to this means for creating a magneto motive force is rotated about an axis parallel to the direction of flux and this is brought about preferably by a rotor having a plurality of pairs of lobes, certain of which are magnetically connected with one pole of the permanent magnet, while the other lobes are magnetically connected with the other pole of the magnet. Associated with the fixed current generating coil are pole pieces which are so related to the rotor that said rotor will intermittently complete the path of the rotating flux portion through the current generating coil and these pairs of lobes are disposed at such angles relative to each other as to cause this intermittent completing of the path of the flux at unequal angular intervals in the rotation of said rotor. Also, associated with the rotor is an interrupter which interrupts the primary circuit of the generating coil at the same angular intervals as the intermittent completing of the path of the flux through the coil by the rotor. Also, associated with the rotor is a distributor which connects the secondary coil alternately with the spark plugs of the engine and in timing with the interrupting of the primary circuit.

Associated with the current generating coil is a condenser and the condenser is supported by the generating coil, so that it may be removed from the magneto without being disconnected from the generating coil. The distributor includes pins which are connected to the generating coil and these pins are carried by insulating material, which is so attached to the generating coil as to be removed with the coil without requiring disconnection of the pins from the said generating coil. It will thus be seen that the generating coil portions of the distributor

and the condenser may all be removed as a unit.

Referring more in detail to the drawings, I have shown my invention as embodied in 5 a magneto ignition device, which includes a supporting base 1, on which are mounted permanent magnets 2. Supported so as to rotate on said base 1 is a rotor 3, which is preferably connected to the engine shaft, so 10 as to rotate at half the speed of the engine shaft. This rotor 3 is carried by a shaft 4, which runs in ball bearings 5 and 6. The ball bearing 5 is mounted in a holder 7, while the ball bearing 6 is mounted in a holder 8. Suitably mounted on the base 1 are pole pieces 9 and 10. These pole pieces 15 support a core 11, on which is mounted a primary generating coil 12 and a secondary generating coil 13. Associated with the 20 generating coils and supported by structure carried by the core 11 is a condenser 14. The core is removably secured to the pole pieces 9 and 10, so that the generating coil may be readily removed from the magneto and 25 when the coil is removed the condenser will be removed therewith.

The pole pieces 9 and 10 are provided with pole faces 15 and 16, which coöperate with the lobes of the rotor. The rotor 10 is provided with two pairs of lobes 18, 19, and 20, 30 21. The rotor turns in the direction of the arrow, as indicated in the figures of the drawings. Let us suppose that the lobes 20 and 21 are the N. lobes, while the lobes 18 and 19 are the S. lobes. The N. lobes are 35 so placed that the angle from center to center is $180 - \frac{X}{2}$ where X is the angular displacement between the engine cylinders. 40 The S. lobes are similarly disposed. When the rotor is in the position shown in Fig. 3, the lobes 18 and 20 are breaking from the pole faces 15 and 16, respectively, and at this time there is a maximum current generation in the primary coil, an interrupter 45 is in circuit with the primary coil and is so timed as to break the circuit just at this maximum period of current generation.

The interrupter is shown more or less 50 diagrammatically in the drawings and consists of a cam 22, mounted on the shaft 4, which operates on a fiber block 23, carried by an arm 24, on which is mounted one of the contacts 25 of the interrupter. The 55 other contact 26 of the interrupter is stationary. The primary circuit is indicated at P in Fig. 3 of the drawings, and it will be noted that this primary circuit is connected to the fixed contact of the interrupter. The other contact of the 60 interrupter is grounded. In Fig. 3 of the drawings, the cam 22 turns in the direction of the arrow and is about to lift the arm 24 and separate the contacts to break the primary circuit. This occurs, as above noted,

just as the lobes 18 and 20 are breaking away from the pole faces 15 and 16.

Also, associated with the rotor, as above noted, is a distributer. This distributer includes a lever 27, which is mounted on a 70 hardened steel pin 28, carried by the bearing holder 7. The lever 27 is actuated by an eccentric 29, carried by the shaft 4. Adjacent the upper end of the lever 27 there is a metallic strip 30, which is adapted to co- 75 operate with the pins 31 and 32. Also carried by this lever 27 is a metallic strip 33, which is adapted to coöperate with the pins 34 and 35. These pins are mounted in a fiber block, which is mounted on a single 80 structure supported by the core of the coil, so that the fiber block, the coil and the condenser are all removed as a unit without requiring any disconnection of the pins in the fiber block with the generating coil. 85 The pins 31 and 34 are connected to a bar 36, which in turn is connected to the secondary generating coil. The pin 32 is connected to a terminal 37 which in turn is connected with one of the spark plugs and the pin 35 is connected with a terminal 38, which in turn is connected with the other spark plug. The two spark plugs are indicated at S and S', in Fig. 3 of the drawings. Inasmuch as the lever 27 is swung by an eccentric 95 member and the metallic strips 30 and 33 will yield to a certain extent after being brought into engagement with the pins, this lever 27 is so timed as to swing into contact with the pins first to the right, as 100 viewed in Fig. 3 and then the pins at the left, and will remain in contact with said pins during a considerable time interval. In other words, the eccentric is at a dwell, so far as movement is imparted to the lever 27, 105 while the metal strips are in contact with the pins. This long time interval permits a wide range in the time interval of the spark. Furthermore, inasmuch as the circuit between the secondary coil and the spark plug 110 S', for instance in Fig. 3, is broken at two points, the spark, in order to jump to the wrong cylinder, must cross this double air gap and this insures that the spark will pass to the right cylinder only, even though 115 the lever 27 be given a comparatively short swing.

The parts are shown in position in Fig. 3 for producing the spark at the spark plug S, and the contacts are just about to separate to interrupt the primary circuit to bring about the spark at this plug. When the rotor turns through a partial rotation, so as to bring the lobe 18 into position to break away from the pole face 15, the lobe 120 21 is bridging the air gap between the pole faces and the cam 22 is now positioned so as to close the contacts and said contacts remain closed during this interrupting of the flux flow through the generating coil and no 125 130

spark is produced. When the rotor is turned to the position shown in Fig. 5, it has passed through an angular distance from the position shown in Fig. 3 of $180^\circ + \frac{X^\circ}{2}$, and the interrupter cam is in position so as to separate the contacts 25 and 26 and break the primary circuit. At this time the lever 27 is shifted to the extreme left-hand position and the metallic strip 33 is in contact with the pins 34 and 35, so that a spark is produced at this time at the spark plug S'. A continued movement of the rotor brings the lobe 19 to a position where it breaks away from the pole face 15, but at this time the interrupter is closed, as indicated diagrammatically in Fig. 6, and no spark is produced. When the rotor turns to the position shown in Fig. 3, it has turned through an angle of $180^\circ - \frac{X^\circ}{2}$ from the position shown in Fig. 5. It will thus be seen that by the positioning of the lobes of the rotor, I am able to secure an intermittent completing of the path of the flux rotated by the rotor through the generating coil at unequal angular intervals and also at angular intervals corresponding to the angular intervals between the cylinders in the engine. It will also be noted that the generating coil is stationary and may be readily removed with the condenser and the distributor terminals without disconnecting any parts thereof.

Particular attention is called to the fact that I have in my magneto electric generator a constant magneto motive force constituting a fixed magnetic field and a portion of the flux due thereto is rotated about an axis parallel to the direction of the flux and the rotating means is so constructed and proportioned as to bring about the intermittent completing of the path of said flux portion through this fixed or stationary generating coil at the angular intervals desired. There is no waste flux producing material as the flux is not shifted from one portion of the generating element to another, as in the Honold structure. While there may possibly be some little difference in the flux changes at the sparking intervals—owing to the shaping of the lobes, there is, however, a much less sacrificing of the efficiency of the current generated, due to excessive air gaps, as in the Cunningham structure, and, of course, the sparks may be advanced or retarded through a greater range of efficient action than in the Cunningham structure. Furthermore, I have been able to secure all the advantages of the maximum current generation at unequal angular intervals of both Honold and Cunningham in a magneto electric generator, which is much more efficient, much more economically made, and

wherein the generating coil is very much more accessible.

The ball bearing holder 8 is reamed out and adjacent said holder is a fiber plate having a sleeve extending into the bearing support. Mounted on this fiber plate are the make and break contacts of the interrupter. By shifting the fiber plate the time of the interruption of the circuit may be varied and thus the spark advanced or retarded.

In Figs. 7 and 8 of the drawings, I have shown a slightly modified form of the construction of the rotor. In these figures, the rotor is provided with lobes arranged in pairs, as above described. All the lobes, however, are of the same size and extent, but the intermittent completing of the flux path at unequal angular intervals is accomplished through the unequal angular spacing of the lobes without any enlargement of the lobes, as in the form of rotor described in detail above. It is believed that the operation of the magneto generator so constructed is obvious and like parts have been similarly numbered and further description thereof will not be given.

It is obvious that minor changes in the details of construction and the arrangement of parts may be made without departing from the spirit of the invention, as set forth in the appended claims.

Having thus described my invention, what I claim as new and desire to secure by Letters Patent, is:

1. An ignition generating device comprising means for creating a constant magneto motive force constituting a fixed magnetic field, means for rotating a portion of the flux due thereto about an axis parallel to the direction of flux, a stationary current generating coil, and means for intermittently completing the path of said flux portion through said coil at unequal angular intervals in the rotation of said flux.

2. An ignition generating device comprising means for creating a constant magneto motive force constituting a fixed magnetic field, means for rotating a portion of the flux due thereto about an axis parallel to the direction of flux, a stationary current generating coil, means for intermittently completing the path of said flux portion through said coil at unequal angular intervals in the rotation of said flux, an interrupter, and means for operating the interrupter at angular intervals corresponding to the angular intervals of flux change and angular intervals of desired ignition.

3. An ignition generating device for an internal combustion engine having its cylinders inclined to each other, comprising means for creating a constant magneto mo-

- tive force constituting a fixed magnetic field, means for rotating a portion of the flux due thereto about an axis parallel to the direction of the flux, a stationary current generating coil, and means for intermittently completing the path of said flux portion through said coil at angular intervals corresponding to the angular position of the engine cylinders, a distributor for distributing the sparks alternately to the cylinders and an interrupter for interrupting the primary circuit of the generating coil at angular intervals corresponding to the position of the engine cylinders.
15. 4. An ignition generating device comprising means for creating a constant magneto motive force constituting a fixed magnetic field, a rotor having lobes for rotating a portion of the flux due thereto about an axis parallel with the direction of the flux, a stationary current generating coil, pole pieces associated therewith and having pole faces coöperating with the rotor, the lobes of said rotor being shaped and positioned so as to intermittently complete the path of flux through said pole faces at unequal angular intervals.
20. 5. An ignition generating device comprising means for creating a constant magneto motive force constituting a fixed magnetic field, a rotor having lobes for rotating a portion of the flux due thereto about an axis parallel with the direction of the flux, a stationary current generating coil, pole pieces associated therewith and having pole faces coöperating with the rotor, the lobes of said rotor being shaped and positioned so as to intermittently complete the path of flux through said pole faces at unequal angular intervals, an interrupter, and means for operating the interrupter at angular intervals corresponding to the angular intervals of completing the flux path through the generating coil, and corresponding to the angular intervals of desired ignition in the engine cylinders.
25. 6. An ignition generating device comprising permanent magnets for creating a fixed magnetic field, a rotor associated with the magnets for rotating a portion of the flux due thereto about an axis parallel to the direction of the flux, said rotor having spaced magnetically disconnected lobes, a stationary current generating coil, pole pieces associated therewith and having pole faces coöperating with said lobes, said lobes being constructed and spaced so as to pro-
- duce an intermittent completion of the path of the flux, due to said magnets through said coil at unequal angular intervals.
7. An ignition generating device comprising permanent magnets for creating a fixed magnetic field, a rotor associated with the magnets for rotating a portion of the flux due thereto about an axis parallel to the direction of the flux, said rotor having spaced magnetically disconnected lobes, a stationary current generating coil, pole pieces associated therewith and having pole faces coöperating with said lobes, said lobes being constructed and spaced so as to produce an intermittent completion of the path of the flux due to said magnets through said coil at unequal angular intervals, an interrupter, and means for operating said interrupter for interrupting the primary circuit of the generating coil at angular intervals corresponding to the intervals of the completion of the flux path and corresponding to the desired intervals of ignition in the engine.
8. An ignition generating device comprising permanent magnets, a rotor associated with said magnets, a stationary coil, pole pieces associated with said coil and having pole faces coöperating with said rotor, said rotor including two pairs of lobes, the lobes in each pair being arranged with their centers at less than one hundred and eighty degrees apart and disposed relative to said pole faces so as to break from the pole faces at unequal angular intervals.
9. An ignition generating device comprising permanent magnets, a rotor associated with said magnets, a stationary coil, pole pieces associated with said coil and having pole faces coöperating with said rotor, said rotor including two pairs of lobes, the lobes in each pair being arranged with their centers at less than one hundred and eighty degrees apart, and disposed relative to said pole faces so as to break from the pole faces at unequal angular intervals, one of said lobes being extended so that the pairs of lobes will break from the pole faces simultaneously and twice during each rotation of the rotor and at unequal angular intervals.

In testimony whereof I hereunto affix my signature in the presence of two witnesses.
